L. Grafton Hardy
Attorney.

UNITED STATES PATENT OFFICE

JOHN J. BROWN, OF EAST RUTHERFORD, NEW JERSEY

CLOTHESLINE SUPPORT

Application filed October 15, 1928. Serial No. 312,541.

The invention relates to certain new and useful improvements in clothes line supports and the principal object of the invention is to provide a window support for clothes lines which is adapted for attachment to any ordinary window casement, quickly and easily without injury to the same.

Another object of the invention is to provide a device which may be easily and cheaply constructed of any suitable material and when not in use, may be swung outwardly, at right angles to the window, leaving an unobstructed view from the same and not interfering with the closing of the window.

15 A further object is to provide means automatically operable to hold the device against objectionable swinging when in its outward position.

20 A further object is to provide means automatically operable to urge the device toward its full outwardly swung position when manually moved toward said position.

25 A further object is to provide means automatically operable serving to hold the device in its inwardly swung position.

30 A further object is to so construct the device that it will be equally efficient in operation, and equally applicable, when applied to either the right hand or left hand side of a window frame.

35 A further and more detailed object is to so construct the device that it will include a pulley arm, a single-piece bracket therefor adapted to be connected with the window frame, a guide pulley for retaining and guiding the upper lead of the clothes line rope, a single pivot pin carried by the bracket constituting a common pivot element for said arm and said guide pulley, and to so arrange 40 said parts that they may be readily assembled and disassembled.

45 With these and other objects in view the invention consists of the novel combination and arrangement of parts which will be set forth in the following specifications and accompanying drawings in which:

50 Fig. 1 is a sectional view through a window illustrating this improved device in its operative position ready to attach the articles of clothes thereto.

Fig. 2, is a view of the device in the inoperative position or when it is allowed to swing outward, when the clothes are on the line.

Fig. 3, is a sectional view of window from interior of room showing an end view of this improved device and the manner in which it is held firmly in the operative position.

Fig. 4, is a side view of bracket, drawn to show the concave in the lower lug which will be fully hereinafter described.

Referring to the drawing, the numeral 1 Fig. 1, designates a window of the ordinary construction, provided with the usual upper sash, 2, and lower sash, 3. Secured to the window frame with two screws, 4 and 4 is the bracket, 5, which is best illustrated in Fig. 4, consisting of a flat oblong plate having cast, or otherwise suitably fastened thereon, three lugs, 6, 7 and 8, the above mentioned bracket, 5 is secured to the window frame 1, in such a manner that the guide pulley, 9, is slightly below the bottom of the two sash 2 and 3, when both are raised to their full height, as clearly shown in Fig. 1.

This arrangement of the bracket 5, allows 75 a free swing through the open window of the supporting arm 10, which will be more fully hereinafter described.

The supporting arm 10 Fig. 1, above referred to consists of a flat rod having at the free end a pulley 11, and at the other end two pivoting lugs, 12 and 12. These two lugs are supplied with suitable pin holes to enable the supporting arm 10, to be pivoted upon the bracket 5, at 7 and 8 by the pin 13 as clearly 85 shown in Fig. 1.

The pivot pin 13 extends through all three of the lugs 6, 7 and 8 and constitutes a common support for the pulley 9 between lugs 6 and 7 and for arm 10 between lugs 7 and 8. 90 Its insertion holds these parts assembled, and likewise its removal permits disassembly of said parts.

This supporting arm, 10 is adapted to support the pulley 11, over which the upper run of the clothes line 14, passes, as shown in Fig. 1. The hook 15, Fig. 1, is adapted to hold the tension on the lower run of the clothes line, 14 when the device is swung outward in its 100

inoperative position as clearly shown in Fig. 2.

When the bracket 5, has been secured to the window frame 1 and the supporting arm 10 pivoted thereto as clearly shown in Fig. 1, the supporting arm 10, is held in the operative position shown in Fig. 1, by the hook 16, and the screw eye 17, Fig. 3. One end of the clothes line 14, is passed behind the small guide pulley 9, Fig. 1, then over the pulley 11. The other end of the clothes line is passed over pulley 18, on the supporting pole 19, the two ends of the clothes line are brought together and secured at the desired tension by a knot 20 as clearly shown in Fig. 1.

It is apparent from the foregoing that this device, as shown in Fig. 1, is in position to hang the clothes thereon, beginning at the knot 20 after the desired number of clothes have been put on the line 14, it will be apparent that the lower run of the line may be easily hooked over the hook 15. The hook 16, is released from the screw eye 17 and the supporting arm 10 allowed to swing outward to the position clearly shown in Fig. 2.

The hook 15, Fig. 2, is placed, approximately, three inches from the pivot pin, 13. Thus it will be apparent that, while there will be a slight slackening of the tension on the line 14, when the device is in the inoperative position, the weight and pull of the line will maintain the supporting arm 10, in the direction of the pole 19, as clearly shown in Fig. 2.

As shown in Fig. 3, the hook 15, is double so the device may be attached to the right or left side of the window frame. The screw eye 17, Fig. 2, is supplied with a nut 22, Fig. 1, which may be removed and the screw eye 21 reversed if necessary.

As window frames vary in depth two extra holes 23, and 24, Fig. 2 are provided; the screw eye 21, may be used in the one most convenient.

The bottom pivot lug 12, on the supporting arm 10 is downwardly convex on the bottom and the pivot lug 8 on the bracket 5 is concave on the top substantially as shown. When the supporting arm 10, is in the inoperative position the convex bottom of the lug 12, Fig. 2 engages with the concave in the top of the lug 8 on the bracket 5 as clearly shown in Fig. 2. The object is to prevent a swaying motion of the supporting arm 10 during a high wind.

As clearly shown in Fig. 2, there is sufficient space between the top of the top lug 12, on the supporting arm 10 and the bottom of the lug 7 on the bracket 5 to afford the necessary slight lifting movement of the supporting arm 10 when said arm is being swung between its opposite positions.

While the convexed and concaved portions of the arm and bracket are, of course, elongated in order to properly perform their function it is important to note that they co-

operate, when the arm is swung to its inner or operative position, to hold the arm in said position, they being in this regard auxiliary to the latch 16.

The convexed and concaved portions thus co-operate with each other to hold the arm in either of its extreme positions.

It will be apparent from the foregoing that a very simple and efficient clothes line support is provided which will enable the clothes to be hung on the same without necessitating the person using the device leaning out of the window.

While in the foregoing there has been shown and described the preferred embodiment of this invention, it is to be understood that such changes may be made in the combination and arrangement of parts as will fall within the spirit and scope of the appended claims.

What is claimed is:

1. A clothes line support of the type concerned comprising a supporting arm, a clothes line pulley rotatably mounted upon said arm to receive a clothes line thereabout providing upper and lower leads for said clothes line, a bracket adapted to be connected with a window frame, a guide pulley for retaining and guiding the upper lead of the clothes line, means by which the arm is pivotally connected with the bracket to swing between operative and inoperative positions, and means connected to the arm off-set from the pivot means by which to utilize the tension of the clothes line for holding the arm in one of said positions.

2. A clothes line support of the type concerned comprising a supporting arm, a clothes line pulley rotatably mounted upon said arm to receive a clothes line thereabout providing upper and lower leads for said clothes line, a bracket adapted to be connected with a window frame, a guide pulley for retaining and guiding the upper lead of the clothes line, means by which the arm is pivotally connected with the bracket to swing between operative and inoperative positions, and means carried wholly by the arm and off-set from the pivot means by which the lower lead of the clothes line may be connected with said arm to utilize the tension of the clothes line for holding the arm in one of said positions.

3. A clothes line support of the type concerned comprising a supporting arm, a clothes line pulley rotatably mounted upon said arm to receive a clothes line thereabout providing upper and lower leads for said clothes line, a bracket adapted to be connected with a window frame, a guide pulley for retaining and guiding the upper lead of the clothes line, means by which the arm is pivotally connected with the bracket to swing between operative and inoperative positions, and a hook provided upon said arm at a point

intermediate the pivot forming means and the clothes line pulley adapted to be engaged by the lower lead of the clothes line to thereby utilize the tension of the clothes line for holding the arm in one of said positions.

5 4. A clothes line support of the type concerned comprising a supporting arm, a clothes line pulley rotatably mounted upon said arm to receive a clothes line thereabout 10 providing upper and lower leads for said clothes line, a bracket adapted to be connected with a window frame, means for retaining and guiding the upper lead of the clothes line, a pivot pin by which the arm is pivotally connected with the bracket to swing between operative and inoperative positions, the bracket and arm having co-operative convexed and concaved surfaces adapted to interengage with each other constituting 15 20 means tending to define said positions of the arm and a hook provided upon said arm removed from the pivot detachably engageable by the lower lead of the line for thereby urging the arm to one of its positions.

25 In testimony whereof, I affix my signature.
JOHN J. BROWN.
